No. 733,782.

PATENTED JULY 14, 1903.

J. P. WERNER & W. H. SILVEY.
TELEPHONE LINE CONTACT APPARATUS.

APPLICATION FILED FEB. 21, 1903.

NO MODEL.

UNITED STATES PATENT OFFICE.

JOSEPH P. WERNER, OF CLIFTONFORGE, AND WILLIAM H. SILVEY, OF LOWMOOR, VIRGINIA.

TELEPHONE-LINE CONTACT APPARATUS.

SPECIFICATION forming part of Letters Patent No. 733,782, dated July 14, 1903.

Application filed February 21, 1903. Serial No. 144,381. (No model.)

To all whom it may concern:

Be it known that we, JOSEPH P. WERNER, residing at Cliftonforge, and WILLIAM H. SILVEY, residing at Lowmoor, in the county of 5 Alleghany and State of Virginia, citizens of the United States, have invented certain new and useful Improvements in Telephone-Line Contact Apparatus; and we do declare the following to be a full, clear, and exact description of the invention, such as will enable others skilled in the art to which it appertains to make and use the same, reference being had to the accompanying drawings, and to the letters of reference marked thereon, which form 10 a part of this specification.

This invention relates to new and useful improvements in an interstation contact apparatus for connection with a telephone-wire adapted to afford means for connecting up 20 with a telephone-wire at any location along the line and telephoning to the station.

More specifically, the invention comprises a metallic contact-clamp mounted upon a pole and having electrical connection with a telephone instrument, while the metallic clamping members are adapted to contact with and receive the current from the telephone-line. 25

Our invention is clearly illustrated in the accompanying drawings, which, with the letters of reference marked thereon, form a part 30 of this application, and in which drawings similar letters of reference indicate like parts in the views, in which—

Figure 1 is a side elevation of our improved 35 contact apparatus as connected to a telephone-wire. Fig. 2 is an enlarged detail view, partially in section, showing the detailed construction of the contact member; and Fig. 3 is a sectional view on line 3-3 of Fig. 1.

Reference now being had to the details of the drawings by letters, A designates a pole which may be of sufficient length to reach 40 from the ground to a telephone-wire, and mounted upon one end of said pole is a metallic plate B, the upper end of which is bent, as shown in Fig. 2 of the drawings, to form a hook C, adapted to engage over a telephone-wire D. A clamping-bar E is fastened to the pole by means of the bolts F, which pass 45 through the plates B and E, as shown in the drawings, and a suitable insulation Q is in-

terposed between the plates and the pole and the screws. Mounted in the bent end of the plate C is a bar C', and the free end of the flexible bar E is grooved, as at K, and adapted to be guided in its movements by said rod. Said bar also serves to prevent the telephone-line wire D from passing over the free end of the flexible bar when the latter is drawn laterally as the hooked plate is pulled down 60 over the wire. An electric wire H is fastened on one of the poles N and is covered with a suitable insulation H' and is adapted to be connected with the instrument M, as shown in Fig. 1 of the drawings. 65

In operation when it is desired to make connection with a telephone-line between stations the operator takes the pole and hooks the contact-plate over the wire, as shown in Fig. 2, and as the hook is pulled down over 70 the wire the bar E or flexible tongue yields, being of a flexible material, and securely clamps the wire between the free end of said bar and the hooked portion C of the plate B, thus having an electrical contact with the 75 telephone-line, and by reason of the metallic connections between said bar and plate and with the wire H communication may be had from the instrument through the wires to the line and with the instruments at the various 80 stations.

While we have shown in the drawings a telephone receiver and transmitter applied to the pole, it will be understood that if desired the instrument may be placed at any 85 suitable location upon a car or other place from which it may have electrical connections with the metallic clamping-plates mounted upon the pole. It will be obvious also that we may make various alterations in the 90 detailed construction of the device without departing from the spirit of the invention.

Having thus fully described our invention, what we claim as new, and desire to secure by Letters Patent, is—

1. An interstation-telephone-line contact apparatus, comprising, in combination with the pole, a metallic hooked plate and a flexible plate bolted thereto and resting upon a shouldered portion of the pole, a convexed 100 guide-bar intermediate the angled portion of said hooked plate, the free end of said flexi-

ble plate being grooved and guided upon said bar, the outer face of said flexible plate adapted to clamp and hold a conductor-wire against the downwardly-bent end of the hooked plate, 5 as shown and described.

2. An interstation-telephone-line contact apparatus, comprising, in combination with a pole, a metallic plate having a shank portion bolted to said pole, its upper portion being bent at right angles, thence downward with its free end outwardly curved, a convexed guide-bar positioned intermediate the angled portions of said plate, a flexible plate bolted to said pole having an outwardly-bent 10

portion coöperating with the free end of the other plate to guide a conductor-wire into the space between the flexible plate and the downwardly-bent free end of the adjacent plate, the end of the flexible plate being grooved to receive said guide-bar, as shown and described. 15

In testimony whereof we hereunto affix our signatures in presence of two witnesses.

JOSEPH P. WERNER.
WILLIAM H. SILVEY.

Witnesses:

W. W. PENDLETON,
W. C. MOODY.
